UNITED STATES PATENT OFFICE.

JAMES H. McCONNELL, OF PULTENEY, NEW YORK.

COMBINED CANE AND STOOL.

SPECIFICATION forming part of Letters Patent No. 686,006, dated November 5, 1901.

Application filed March 13, 1901. Serial No. 50,954. (No model.)

To all whom it may concern:

Be it known that I, JAMES H. McCONNELL, a citizen of the United States, residing at Pul-
tene, in the county of Steuben and State of
5 New York, have invented certain new and
useful Improvements in a Combined Cane
and Stool; and I do declare the following to
be a full, clear, and exact description of the
invention, such as will enable others skilled
10 in the art to which it appertains to make and
use the same, reference being had to the ac-
companying drawings, and to the letters of
reference marked thereon, which form a part
of this specification.

15 This invention relates to an improved com-
bined cane and stool.

An object of the invention is to provide in
a construction of this character a sectional
20 seat portion adapted to be partly folded to
constitute a handle, but when open will af-
ford an extensive flat surface.

This invention has for its further object
the provision of an improved locking means
25 for securing the handle-sections when closed
against accidental folding.

The invention still further embraces the
idea of a novel folding means whereby the
30 legs of the stool may be folded to occupy the
least possible space or extended as desired to
give the proper length of cane.

Improved details in the arrangement and
construction of the several parts will be ap-
parent from the detailed description herein-
35 after and the appended claims, when taken
in connection with the accompanying draw-
ings, forming part hereof.

In the drawings the preferable embodiment
of the invention is shown for the purpose of
40 illustration, and when hereinafter referring to
the same like reference characters will refer
to corresponding parts in the several views.

Figure 1 is a perspective view of the con-
struction in open position, the same consti-
50 tuting a stool. Fig. 2 is a perspective view
of the same in folded position, the central leg
being extended, as when used as a cane. Fig.
3 is a sectional view on the line xx of Fig. 1.
Fig. 4 is a detail view of the seat-section and
55 the upper portions of the legs, and Figs. 5
and 6 are detail views.

Referring more specifically to the drawings,
A designates a metallic casting provided with

suitably-disposed ears a , between which are
pivoted supporting-legs B of any desired de-
scription, those shown being rectangular in 55
cross-sections to prevent twisting of the same
at the pivoted points. Upon the upper sur-
faces of the casting A is secured a metallic
plate C, of rectangular shape, upon which
rests the central stationary portion d of the 60
seat D. The respective ends of the plate C
extend a short distance beyond the edges of
the portion d and are turned up at e , said
turned-up portion being provided with suit-
able perforations in which work pivots e of 65
metallic brackets d' , secured, respectively, to
substantially U-shaped sections $d^2 d^3$ of the
seat portion, the same being adapted to oc-
cupy a horizontal position, as shown in Fig.
1, when the stool is to be used and to occupy 70
a vertical position (shown in Fig. 2) when
constituting a handle for the cane. To lock
the sections $d^2 d^3$ in the last-mentioned position,
a catch F, pivoted at f to the plate C, is
provided, the same having at its end the fin-
gers f' , adapted to overlie the outer surfaces
20 of the adjacent brackets on the seat-sections
and snugly fit the same. The catch is cut
away, as at f^2 , to fit over the pivot-nut, as
shown. The central leg G is loose and slid-
ably engages a depending guide-rod H, free
80 at its lower end and secured at its upper end
at a suitable point on the casting A. The
guide-rod passes through a longitudinally-dis-
posed opening h in the central leg G, formed 85
by the corner thereof being cut away, and the
angle-iron g fitting thereover, as shown in Fig.
3. A sleeve I slidably engages the leg G and
carries at its lower end a casting i , the same
being held in adjusted positions through the 90
medium of a thumb-bolt i' , engaging one of
the surfaces of the angle-iron on said leg.
To the upper surface of the casting brace-
rods K are pivotally secured at k at one end
and at the other end are correspondingly se-
95 cured at k' to the legs B at points interme-
diate the ends of the same. The sleeve is
limited against excessive downward move-
ment by a stop i^2 on the leg G.

When the construction is to be used as a 100
cane, the sleeve is dropped into the position
shown in Fig. 2, when the brace-rods will draw
the legs inwardly to fold the same and the
leg G will be slid upon the guide-rod H down-

- wardly through the sleeve to make the proper length of cane. The leg G is held in adjusted positions by the thumb-bolt i' referred to engaging in one of a series of sockets l in the 5 surface thereof. The legs are held against outward movement by a ring L, which is sprung over the screw-heads l' of the brackets l^2 , in which the brace-rods for the legs are pivotally secured.
- 10 Having thus described the invention, what is claimed as new, and desired to be secured by Letters Patent, is—
1. A combined stool and cane comprising suitable legs or supports, a seat secured at 15 the upper end thereof comprising a central stationary section, a plate below said central stationary section and extending beyond the sides thereof, end sections of the seat pivoted to the extensions of the plate adapted to fold 20 upwardly, and a pivoted catch provided with projecting fingers adapted to overlie the ends of the pivoted sections to lock the same in folded position, substantially as described.
  2. A combined stool and cane comprising 25 suitable seat and handle portions, legs pivotally secured thereto, a centrally-arranged leg immovable laterally, an adjustable sleeve on said central leg, pivoted brace-rods connecting the sleeve and legs, oppositely-disposed 30 projections on the legs and a ring slidable on the exterior surfaces of the legs adapted to

be sprung over and fit between the projections thereon to lock the same in folded position, substantially as described.

3. A combined cane and seat comprising a 35 suitable seat and handle portions, legs pivotally secured to said seat portion a guide-rod depending from said seat portion, a central leg slidably engaging said guide-rod, a sleeve on said central leg, means for clamping the 40 sleeve in adjusted position upon said leg and pivoted brace-rods between the sleeve and the respective pivoted legs, substantially as described.

4. A combined cane and seat comprising a 45 suitable seat and handle portions, legs pivotally secured to said seat portion, a depending guide-rod suspended from said seat portion, a centrally-arranged leg provided to one side thereof with a guide-opening adapted to work 50 upon said guide-rod, a sleeve on said central leg, connection between the sleeve and the pivoted legs, and means for clamping the sleeve in adjusted position, substantially as described.

55 In testimony whereof I affix my signature in presence of two witnesses.

JAMES H. McCONNELL.
